Des. 179,363
Patented Dec. 4, 1956

179,363

COMBINED CIGARETTE HOLDER AND FILTER

Booker T. Tyree, Los Angeles, Calif.

Application May 21, 1956, Serial No. 41,572

Term of patent 14 years

(Cl. D85—8)

FIG' 1

Fig. 1 is a perspective view of a combined cigarette holder and filter showing my new design; and

Fig. 2 is a top plan view thereof.

I claim:

The ornamental design for a combined cigarette holder and filter, as shown.
